UNITED STATES PATENT OFFICE

LEIF BJARNE KLAUSSEN, OF MINDE, NEAR BERGEN, NORWAY

APPARATUS FOR TURNING OF LEAVES OF MUSIC

Application filed January 11, 1929, Serial No. 331,865, and in Norway October 4, 1927.

The present invention relates to an apparatus for turning of leaves of music, adapted to be secured to the music stand of a piano or the like or to a usual music rest.

5 The invention is by way of example illustrated in the annexed drawings where

Fig. 1 is a front view of the device,

Fig. 2 is a plan view thereof,

10 Fig. 3 diagrammatically illustrates the wire arrangement, and

Fig. 4 is an end view of the device secured to a music stand.

At the drawings 1 designates the lower plate and 2 the top plate of the device, which 15 plates are interconnected and held at a suitable distance from each other by means of connecting members 3, the said plates and members constituting the main supporting means of the apparatus. Between said plates 20 1 and 2 are rotatably arranged a top disc and a lower disc 4, 4, one of which may be provided with an arcuated slot 5 (Fig. 3) which cooperates with a suitable abutment pin 5^a to limit the turning movement of the 25 discs.

To the discs 4 and eccentrically to the axis thereof are pivotally secured the music leaf supporting means in the form of two arms 6, 7, the outer ends of which carry clamping 30 carriers or transfer members 8, 9 for the music leaves A to be turned. The inner ends of said arms 6, 7 are U-shaped and one of the prongs thereof passes over and the other under the upper and the lower discs 4, 4 respectively, the cross portions 10 and 11 which connect the prongs being adapted to cooperate with the actuating mechanism for the arms, as will be described more fully below.

Between the discs 4, 4 are arranged two 40 string sheaves 14 and 15 mounted one over the other on studs 12 and 13 respectively and each carrying an arcuated spring 16 and 17 respectively. The outer, free ends of the springs 16 and 17 are bent to form hooks 18 and 19 respectively, which coact with the cross portions 10 and 11 on the arms 6 and 7 respectively when the latter are swung, as will be described below.

At each end of the apparatus is provided 45 a member 21 which is adjustable by means of

a threaded bolt 20 and to which is secured a resilient spring or rubber member 22, to which is again secured a wire or line 23. Each of said lines passes over a guiding roller 24 to the sheave 14 (respectively 15), then over 55 guiding rollers 25, 26 and 27 to the other end of the apparatus, where the line is secured to an impact member 28. Said member 28 may consist of an angle-shaped piece the horizontal part 29 of which is adapted to be 60 pressed down by means of the fingers. Near the end of the line 23 is secured thereto an abutment member 31 which co-operates with an abutment 30 to limit that movement of the line which is caused by the member 22. 65

The apparatus is provided with resilient clamps 32 by means of which it may be secured to the music stand 33 of the piano 34 or the like, as shown in Fig. 4 whereby the impact members 28 will be situated directly 70 above the clavier 35, at a suitable distance therefrom. However, the apparatus may also be adapted to be secured in a similar manner to a usual music rest; the impact members 28 may, if desired, be so arranged 75 that they are adapted to be actuated by means of the elbow, the knee or the foot. In the last case it may be most suitable to connect the lines 23 with a suitable pedal mechanism or the like. 80

If the apparatus is secured to the music stand of a piano and the leaves of music to be turned are secured in the carriers or transfer members 8 and 9 at the arms 6 and 7 respectively, both situated at right in Figs. 1 and 2, the operation of the apparatus is as follows:

The discs 14 and 15 are, due to the tension of the members 22 and the cooperation of the abutments 30 and 31, held in a predetermined normal position indicated in Fig. 2, and due to the excentrical mounting of the arms 6, 7 on the discs 4, 4 by means of individual pivots the cross portions 10 and 11 respectively will be situated at different distances from the axis of the discs 4 when the arms 6 and 7 are swung to the same side (see Fig. 2).

If the leaf secured in the transfer member 9 is to be swung from right to the left, 100

the player presses the right hand impact member 28 down, whereby the disc 14 is turned by the line 23 against the action of the resilient member 22 which at the same time is placed under tension. When the disc 14 is turned it swings the spring 16, which is pressed past the cross portion 11 on the arm 7 until said portion 11 snaps into the hook 18 on the spring 16. When now the impact member 28 is released by the player, the disc 14 turns automatically by the action of the resilient member 22 back to normal position, and the spring 16 when moving back takes with it the arm 7 and accordingly also the leaf of music in question. The shape and action of the spring 16 is so chosen that when the arm 7 has been swung somewhat past its middle position, that is past a position at right angles to the plane of the paper in Fig. 1, the cross portion 11 passes out of the hook 18 and the arm continues due to its momentum.

During the above described movement of the arm 7 the discs 4 are turned somewhat to the right so that the arm 6, and accordingly its cross portion 10, is moved inwardly to the same radial distance from the center of the disc 14 as previously the arm 7 and the cross portion 11 thereof. Therefore, if the right hand impact member 28 is again pressed down the same operations as above described will be repeated and the arm 6 and the transfer member 8 thereof swung from right to the left.

35 The leaves of music may be moved back again in exactly the same manner as above described by actuating the left hand impact member 28.

40 The velocity of the swinging movement of the arms is controlled by means of the threaded bolts 20, which may be adjusted to adjust the tension of the member 22.

45 The apparatus above described is adapted to turn two leaves of music, but it is obvious that it may be constructed for turning of a greater number of leaves, by providing a greater number of arms, the remaining mechanism being in the reality unaltered.

50 If desired only one disc 14 with line and impact member 28 may be provided; the return of the leaves of music being made entirely manually.

55 It is obvious that the details of the apparatus and its construction may be widely varied within the scope of the invention, the embodiment thereof here shown and described only illustrating an example.

Having now particularly described and ascertained the nature of my said invention and in what manner the same is to be performed, declare that what I claim is:

60 1. Apparatus for turning leaves of music including a support, a disc mounted for limited turning movement on the support, a leaf supporting arm having the inner end there-

of pivotally and eccentrically secured to the disc and provided with a cross pin, an actuating mechanism for the arm including a rotatably mounted bowed spring the free end of which is shaped as a double hook 70 adapted to engage the pin on the arm when the spring is swung against the arm, an impact member operably connected with the actuating mechanism for effecting swinging movement against the arm, and a resilient device operably connected with the impact member which as the spring is swung against the arm is placed under tension and automatically swings said spring back to position, substantially as and for the purposes set forth. 75 80

2. Apparatus in accordance with claim 1, wherein a flexible member establishes operable connection between the impact member, the actuating mechanism and the resilient device, and wherein the actuating mechanism also includes a sheave operably connected with the flexible member and having a spring connected thereto. 85

3. Apparatus in accordance with claim 1, 90 wherein a flexible member establishes operable connection between the impact member, the actuating member and the resilient device, and wherein the resilient device is inserted between the end of the flexible member and the support. 95

4. Apparatus in accordance with claim 1, 100 wherein there are two sets of actuating mechanisms and impact members and resilient devices are provided, one set for the movement of the arms in each direction. 105
